Primary Examiner — Antoine Duval Davis

CLAIM

We claim the ornamental design for an asset tracking equipment housing, as shown and described.

DESCRIPTION

FIG. 1 is a first perspective view of an example asset tracking equipment housing;

FIG. 2 is a second perspective view thereof;

FIG. 3 is a bottom view thereof;

FIG. 4 is a top view thereof;

FIG. 5 is a first side view thereof;

FIG. 6 is a second side view thereof;

FIG. 7 is a front view thereof; and,

FIG. 8 is a rear view thereof.

The broken lines are for illustrative purposes only. Broken lines form no part of the design claimed.
